UNITED STATES PATENT OFFICE.

JACOB RATZLAFF AND DAVID E. REED, OF PORTLAND, OREGON.

DRIVING MECHANISM.

1,084,230.

Specification of Letters Patent. Patented Jan. 13, 1914.

Application filed February 15, 1913. Serial No. 748,687.

To all whom it may concern:

Be it known that we, JACOB RATZLAFF and DAVID E. REED, citizens of the United States, residing at Portland, in the county of Multnomah and State of Oregon, have invented certain new and useful Improvements in Driving Mechanism; and we do hereby declare the following to be a full, clear, and exact description of the invention, such as will enable others skilled in the art to which it appertains to make and use the same.

This invention relates to the driving mechanism of motor cars, such as traction engines or automobiles; and it consists of a casing whereby the teeth of the main driving wheel and its pinion are shielded from dirt and gravel as hereinafter fully described and claimed.

In the drawings, Figure 1 is a side view of one of the ground wheels and its main driving wheel provided with a casing according to this invention. Fig. 2 is a cross-section, taken on the line $\alpha-\alpha$ in Fig. 1. Fig. 3 is a detail plan view of one of the brackets which secure one casing disk to the frame, showing also the adjacent parts.

The motor car or traction engine is provided with two main road wheels 2 of any approved construction, which are similar to each other, and which are mounted on the end portions of a shaft 3. The shaft 3 is carried by the main frame 4 of the engine, and the main frame has also similar bearings 5 in which the countershaft 6 is journaled. The main driving wheel is formed of an internal toothed ring 7 having lugs 8 on it, and 9 are brackets secured to the lugs 8 and to the periphery of the ground wheel 2. The countershaft is preferably arranged above the axis of the shaft 3 and a little in front of it; and the countershaft is driven by means of any approved motor and intermediate driving mechanism. A toothed pinion 27 is secured on the countershaft and gears into the toothed ring or wheel 7. When arranged in this manner, and the motor car is driven forwardly, the pressure of the pinion on the teeth of the internal toothed wheel is downward and between the main road wheels and the steering wheel or wheels at the front end of the motor car. This causes the steering wheel or wheels to be pressed downwardly on the ground, as well as engaging with the ground by gravity, and a good frictional contact with the ground is assured. As ordinarily arranged,

the revolution of the driving pinion tends to raise the front end portion of the motor car off the ground.

In order to prevent dirt and gravel from getting between the teeth of the main wheel and its pinion, and causing them to wear out rapidly, the wheel and pinion are enclosed in a casing which is made as nearly dirt proof as possible.

A stationary disk 10 of thin sheet metal is arranged on one side of the wheel 7 and its pinion. This disk 10 has a hole 11 in which the countershaft revolves, and it has a hole 12 provided with a flange 13 which is fitted tightly over a projection 14 on the main frame around the main shaft. The periphery of the stationary disk 10 has a lateral flange 15 secured to it, or formed on it, and this flange 15 incloses one edge of the toothed ring 7 and is fitted snugly to it. Brackets 17 are provided for securing the stationary disk 10 to the frame 4 at suitable intervals. A revoluble disk 18 of thin sheet metal is arranged at the other side of the wheel 7 and its pinion. This disk 18 has a hole 19 at its center for the hub of the ground wheel to project through, and the disk is secured to a circumferential projection 20 on the said hub. The center part 21 of the disk 18 is dished inwardly toward the stationary disk, so as to clear the spokes of the ground wheel, and its periphery is provided with a flange 22 which is fitted tightly over and is secured to the toothed wheel or ring 7. The outer side of the road wheel 2 is closed by a disk 24 which is secured to its periphery, and the inner side of the road wheel is closed by an annular plate 25 which is also secured to the periphery and which is journaled on the flange 15 of the stationary disk 10.

What we claim is:

1. The combination, with a frame, a main shaft and a countershaft carried by the frame, a road wheel mounted on the main shaft, an internal toothed wheel secured to the road wheel, and a toothed pinion secured on the countershaft and gearing into the internal toothed wheel; of a stationary disk provided with a peripheral flange which incloses one edge of the internal toothed wheel, said disk having holes for the said shafts, and a revoluble disk having its central portion secured to the hub of the ground wheel and having its periphery secured to the internal toothed wheel.

2. The combination, with a frame, a main shaft and a countershaft carried by the frame, a road wheel mounted on the main shaft, an internal toothed wheel secured to the road wheel, and a toothed pinion secured on the countershaft and gearing into the internal toothed wheel; of a stationary disk provided with a peripheral flange which incloses one edge of the internal 10 toothed wheel, said disk having holes for the said shafts, and a revoluble disk having its central portion dished inwardly toward

the stationary disk and secured to the hub of the ground wheel, said revoluble disk having also a flange at its periphery which 15 incloses and is secured to the other edge of the internal toothed wheel.

In testimony whereof we affix our signatures, in presence of two witnesses.

JACOB RATZLAFF.
DAVID E. REED.
